UNITED STATES PATENT OFFICE

ANTHONY E. WEINGARTNER, OF BETHLEHEM, PENNSYLVANIA, ASSIGNOR TO AMERICAN ENGINEERING COMPANY, OF PHILADELPHIA, PENNSYLVANIA, A CORPORATION OF PENNSYLVANIA

SUBMARINE LIFE SAVING SYSTEM

Application filed June 15, 1929. Serial No. 371,116.

This invention relates to improvements in submarines, and the principal object of the invention is to provide novel and practicable means permitting escape of the occupants of 5 the vessel in the event of accident preventing bringing the boat to the surface of the water in the usual manner.

To this end, the invention contemplates the provision of means whereby the occupants 10 may be passed from the interior of the vessel to the exterior and brought safely to the surface of the water, said means being such that the said occupants are not subjected to the excessive pressures of the water at great 15 depths.

A more specific object of the invention is to provide a suitable container for the occupants of the craft with means for ejecting or passing said container from the interior 20 of the vessel without admitting water, said container being such as to support the occupants at the surface of the water.

Another object of the invention is to provide a container of the stated type which may 25 be completely and hermetically sealed and which has means in the interior for releasing an upper portion to permit escape of the occupants at the surface of the water.

A still further object of the invention is 30 to provide rescue means as set forth above which shall be effective regardless of the position of the vessel on the floor of the ocean.

The invention further resides in certain 35 novel structural details and features hereinafter set forth and illustrated in the attached drawings, in which:

Figure 1 is a fragmentary side elevational 40 view of the center portion of a submarine equipped with a life-saving device made in accordance with my invention;

Fig. 2 is a section on the line 2—2, Fig. 1;

Fig. 3 is a sectional view similar to Fig. 45 2, showing the vessel in a position which it might assume on the floor of the ocean following an accident;

Fig. 4 is an enlarged fragmentary sectional 50 view illustrating details of the apparatus forming the subject of the present invention;

Fig. 5 is a longitudinal sectional view through one of the containers;

Figs. 6, 7 and 8 are reduced fragmentary sectional views similar to Fig. 4 showing three steps in the operation of ejecting one 55 of the containers;

Fig. 9 is a sectional view illustrating a modification within the scope of the invention;

Fig. 10 is a transverse fragmentary sectional view illustrating a further modification;

Fig. 11 is an elevational view of the parts shown in Fig. 10;

Fig. 12 is a sectional view on the line 65 12—12, Fig. 11, and

Fig. 13 is a view in perspective of an element of the operating mechanism.

With reference to the drawings, Figure 1 is a side elevational view illustrating the mid 70 section of a submarine. The submarine may accord in all respects to the present standards, but departs therefrom in provision in one or more compartments thereof of one or more ports 1. In the present instance, the 75 submarine is shown as being provided in each of two adjacent compartments with four of these ports, see Figure 1 and the sectional view of Figure 2. In the latter figure, the submarine is shown as comprising inner and outer shells 2 and 3, the ports 1 constituting in effect cylindrical passages extending through and between the shells. The details of the port construction are best shown in Fig. 4. As therein shown, a cylindrical flanged sleeve 4 is provided between and secured to the shells 2 and 3, while the outer end of the port is reinforced by a heavy cast collar 5 having an outer flange 6 secured to the outside of the shell 3 and a body portion 7 projecting into the cylindrical sleeve 4. The cylindrical portion 7 is provided with a pair of annular packing members 8 and is adapted for reception of a cylindrical plug 9 which normally seals the port. The plug 9 is prevented from being forced inwardly by external pressure by a plurality of spring or mechanical latches 11 slidably fitted in the inner end of the member 5, these latches being beveled at their outer ends to provide for 80 85 90

95 100

their automatic retraction under pressure exerted from the interior of the vessel to permit expulsion of the plugs 9 and of other parts hereinafter described. It will be noted 5 that the outer face of the plug 9 is provided with a circular recess 12, while the inner end of the plug is provided with transverse crossed flanges 13, the outer edges of which are notched or recessed as indicated at 14 10 for reception of the latches 11 and whose lower edges are also recessed as indicated at 15 for purposes hereinafter set forth.

In the form of device illustrated in Fig. 4, the port is provided at its inner end and at 15 opposite sides with a pair of brackets 16 secured to the shell 2 and to the sleeve 4 as illustrated, which brackets are provided with threaded bosses 17 for reception of the ends of a pair of threaded bolts 18 which project 20 from said sockets towards the interior of the vessel and which are in substantial alignment with the longitudinal center line of the port 1. The threaded members 18 are detachable from the sockets 17 at will. In conjunction 25 with the members 18, I provide a carriage 19 having at opposite sides thereof and supported in suitable bearings for free rotation a pair of worm wheels 21 which are adapted to be threaded on the members 18. 30 The two worms are actuated through the medium of a shaft 22 on which are fixed worms 23 which respectively mesh with the worm wheels 21, the shaft 22 being journaled in suitable bearings in the under part of the member 19 and having at each end a hand wheel 24 by means of which the shaft may be rotated. Rotation of the shaft in this manner results in an advanced or retractive movement of the carriage 19 on and between the 35 threaded members 18. The carriage 19 constitutes a support for a casing 25, this casing, the details of which are shown in Fig. 5, being cylindrical in form and of sufficient length to hold a man in upright position.

45 As shown in Fig. 5, the casing is made up of a plurality of sections numbered for convenience 26, 27, 28 and 29. The base section 26 is closed at the bottom and has a reduced extension 31, the purpose of which will be 50 set forth hereinafter. This base section 26 also has in the interior a false bottom 32 which forms in the bottom of the section a chamber 33 having a port 34 controlled by a valve 35 which projects into the upper chamber. In the present instance, this valve is 55 shown as actuatable by a lever 36 adapted to be opened by the foot of one occupying the casing and being normally closed. The upper open end of the section 26 is threaded for 60 reception of the lower end of the section 27, the joint being such as to provide a hermetic seal and the upper portion of the section 27 is similarly threaded for cooperation with the lower threaded end of the section 28. The 65 top of the section 28 is closed by the top

member 29 which takes the form of a head and which is threaded into the normally open end of the section 28. As clearly illustrated, the section 28 is made up of two semi-cylindrical sections, these sections having inwardly abutting flanges 37 which are securely held together by bolts 38 each provided in the present instance with a wing nut 39. By releasing these nuts 39, the occupant of the casing may easily force away the two halves of the section 28 and the top section 29, thereby leaving the upper end of the section 27 open and permitting escape. The casing is so designed, however, that with the upper sections 28 and 29 removed, the lower portion of the casing will float on the surface of the water in an upright position. Oxygen or compressed air may be introduced into the chamber 33 through a port 41 in the false bottom 32, which port is normally closed by a plug as illustrated. If for any reason it is necessary for one to remain sealed in the casing for any length of time, the oxygen or fresh air in the chamber 33 may be allowed to pass into the main casing chamber by actuation of the valve 35, as set forth above, and a pressure relief valve 42 is provided in the top section 29 to maintain the pressure within the casing at a predetermined point.

It will be noted that the upper end of the section 29 is provided with a cylindrical extension which fits neatly within the recesses 15 in the lower edges of the flanges 13 of the plug 12, which closes the port 1, whereby 100 when the carriage 19 is moved upwardly by actuation of the shaft 22 as described, the upper end of the casing is accurately centered with respect to the port 1. The outer diameter of the casing 25 is the same as that of the plug 12 so that when the upper end of the casing 25 is brought into contact with the inner side of the plug 9 and pressure is exerted through the carriage 19 and associated mechanism, the plug will be forced outwardly past the latches 11 and will be immediately replaced by the casing itself, which maintains the port 1 closed during its outward movement.

In the normal assembly shown in Fig. 4, 115 the lower end of the casing 25 is supported on a plug 9a which is the counterpart of the plug 9 shown closing the port 1, and it will be noted that the lower extension 31 of the bottom section 26 of the casing fits neatly 120 within the socket 12 corresponding to the recess 12 of the plug 9 which is provided for that purpose whereby the plug 9a is held in accurate coaxial relation with the cylinder 25. The various corresponding parts of the 125 plugs 9 and 9a have been designated by the same reference numerals as previously applied to the plug 9. Also in the assembly shown in Fig. 4, the plug 9a rests upon a pedestal element 43 which in the present in- 130

stance rests in a suitable socket in the carriage 19 and which permits movement of the plug 9a into the position of the plug 9 whereby the port 1 is effectively closed following 5 the expulsion of the casing 25. It will be noted that the outer part of the port 1 in the member 5 is slightly flared so that when the plug 9a reaches the normal port-closing position, the casing 25 is free to move upwardly 10 in the water by reason of its own buoyancy. In normal operation of the device as set forth above, it may be assumed that following an accident the submarine is lying on its side on the ocean floor such for example as 15 shown in Fig. 3. Regardless of the position of the submarine, it will be apparent that at least one of the ports 1 will be in position rendering it available for the purpose of expelling the casing 25. Initially, the threaded 20 bolts 18 are screwed into their sockets 17, after which the bevel wheels 21 are threaded onto the lower end of the shafts, thereby bringing the carriage 19 into operative position on the members 18. Thereafter, the pedestal 25 member 43 and the plug 9a are placed in position upon the carriage and one or more of the casings 25 assembled with men in the interior. One of the casings is then placed in position on the plug 9a and the hand wheels 30 24 actuated to bring the top of the casing into engagement with the inner end of the plug 9, thereafter to move the casing upwardly to first displace the plug 9, and thereafter to force the casing through and from the 35 port 1. Before the casing 25 is released, however, the plug 9a moves into position closing the port 1, and is eventually brought to the position of the plug 9, as shown in Fig. 4. Thereafter, the carriage 19 is backed down- 40 wardly on the bolts 18 to a retracted position and a second casing with a second substitute plug placed in position thereon for a repetition of the operation.

In Figs. 6, 7 and 8, I have illustrated more 45 or less diagrammatically three positions of the parts in the operation set forth above. Fig. 6 shows the initial starting position; Fig. 7 shows the casing partly discharged, and Fig. 8 shows the casing completely dis- 50 charged and the substitute plug in position again closing the port 1. The original plug 9 is indicated as loose following displacement by the casing.

In Fig. 9, I have illustrated a modification 55 of the apparatus in which the mechanical means for forcing the casing outwardly through the port is replaced by hydraulic mechanism adapted for the same purpose. In this instance, an inner pressure cylinder 60 45 is provided which may be secured by bolts 46 to the inner end of the port member 5, suitable gaskets 47 being provided between these parts to form a sealed joint therebetween. In this instance, the spring latches 55 11 are mounted in recesses in the upper end

of the cylinder member 45. The inner diameter of the cylinder 45 is only sufficiently larger than the outer diameter of the casing 25 to provide a working fit whereby when hydraulic pressure is applied to the bottom 70 of the cylinder, as hereinafter set forth, the casing 25 in the interior of the cylinder is forced outwardly, first displacing the plug 9 and then itself being forced through the port 1. The lower end of the cylinder 45 is 75 closed by a head 50 which is hinged to the cylinder at 47 in the present instance and which is held in the closed position by a bolt 48. The cylinder is of sufficient length to receive the casing 25 and also the substitute 80 plug 9a as illustrated. It will be noted that the projecting flanges 13 of the plug 9a provide a space in the bottom of the cylinder into which the hydraulic fluid may be forced under the plug 9a. This space is connected 85 through a pipe 49 with the discharge side of a suitable pump 51, which is actuated in the present instance by an electric motor 52. A pipe 53 extends from the outside of the outer 90 shell 3 of the submarine to the intake side of the pump 51, the pipe 53 being controlled by a hand valve 54 in the interior of the vessel. A pump of the Hele-Shaw type will be found entirely adequate for the purpose. The upper end of the cylinder 45 is provided 95 with a port 55 which is connected with the interior of the vessel through a check valve 56 which permits air to enter the cylinder when the pump 51 is reversed to expel the fluid from the interior of the cylinder 45 following ejection of the cylinder 25 and in preparation of the apparatus for ejection of another of the cylinders.

In the modification shown in Figs. 10 to 13, inclusive, the inner and outer shells of 105 the submarine are designated, as in the previous modifications, by the reference numerals 2 and 3. In this instance, a substantially cylindrical chamber 60 is formed between the shells in such positions that both 110 ends may open to the exterior of the vessel, the ends of the chamber normally being closed by closure members 61, 62, which are respectively pivoted on shafts 63 and 64 journaled on the outer side of the outer shell 115 3 of the submarine. Each of these shafts carries a worm wheel 65 which may be operated from the interior of the submarine through the medium of worms 66 carried on shafts 67 which extend through the outer 120 and inner shells of the vessel. A socket wrench 68 is provided in the present instance to turn these shafts 67 in the interior of the vessel. Provision is made for clamping the doors 61 and 62 in the chamber-closing positions from the interior of the chamber, this taking the form in the present instance of clamping spiders 71 which are adapted to bear against internal shoulders in the ends 125 of the cylindrical chamber 60, as illustrated,

and to be secured to the inner sides of the door 61 by means of studs 72 on the latter which in assembly project through aperture in the spider 71 and receive at their inner ends nuts which bear against the inner face of the spiders.

Access to the interior of the chamber or chambers 60 may be had from the interior of the vessel through door plates 73 which are substantially the same in width and height as the corresponding dimensions of the chamber 60. These door plates 73 are preferably hinged at one side, as indicated at 74, and are held in the closed position by means of hinged studs 75 which engage slotted flanges 76 on the door. Bolt clamps 77 are also provided at the top and bottom as illustrated. The doors 73 are also provided at both top and bottom with a valved port 78 for a purpose hereinafter set forth.

Each of the chambers 60 is connected through a pipe 81 with an air pump in the interior of the vessel whereby air may be forced under pressure into the chamber, the pipe 81 containing a check valve 82 which prevents back-flow of the air from the compartment. Each of the compartments is also connected through a pipe 83 with the exterior of the vessel, the respective pipes 83 being provided with valves 84, 84.

In this instance, a waterproof container 25 similar to those previously described is employed, into which one of the occupants of the vessel may be placed, the container 25 then being inserted into the chamber 60, as illustrated. A guide element 85 is carried on the interior of each of the doors 73, insuring a proper alignment of the container 25 within the chamber. Following insertion of the container 25 and the clamping of the door 73 in the closing position, water is admitted to the chamber through the pipe 83, the air within the chamber being displaced through one or other of the valved pipes 78 into the interior of the vessel. When the chamber is completely filled with water and the valved pipe 78 closed off, one or other of the covers 61 or 62, whichever is at the top, is opened through the shaft 67, thereby permitting the container 25 to rise from the chamber by its own buoyancy. Before insertion of the container 25, it will be apparent that the inner clamp 71 of the closure is removed to permit opening of the closure as described. Following escape of the container 25, the closure is again brought to its seat and air under pressure admitted to the chamber through the pipe 81 to force the water from the chamber through the pipe 83 to the exterior of the vessel. Following removal of the water in this manner and closing of the valve 84 to prevent re-entrance of the water to the chamber, the cover plate 73 may be removed to permit insertion

of another of the containers 25, the circle then being completed.

This device constitutes in effect an air lock for passing the containers through the side walls of the submarine, advantage being taken in this instance of the natural buoyancy of the container to cause it to leave the chamber. By arranging the chamber as illustrated so that both ends thereof are available for the discharge of the container 25, the chamber is available in reverse positions of the submarine and does not depend for operativeness upon a given position of the latter. By having several of these locks distributed in spaced relation around the circumference of the submarine, it will be apparent that one will always be available for use regardless of the position that the submarine may assume.

I claim:

1. A submarine vessel comprising a port, an outwardly displaceable plug normally closing said port, a substitute plug, means for forcing said substitute plug outwardly to displace the first-named plug and to replace said plug in closing the port, and a hollow cylinder having substantially the same diameter as said plug and adapted to be forced through said port in advance of the replacing plug, said cylinder being effective to seal the port during transit therethrough.

2. The combination with a submarine vessel having a port in an outer wall thereof, an outwardly displaceable plug normally sealing said port, means preventing inward displacement of said plug by external pressure, said means being retractile to permit movement outwardly through said port, a hollow cylinder corresponding in diameter with said plug, means for forcing said cylinder outwardly in coaxial relation with said plug whereby the latter is displaced from the port and is replaced in the port-sealing function by said cylinder, and a replacement plug adapted to be forced into said port after the cylinder to replace the latter and to maintain the port closed.

3. In a safety device for submarine vessels, the combination with a wall construction providing a cylindrical port from the interior to the exterior of the vessel, a cylindrical plug accurately fitting said port and normally closing the latter, a hollow cylindrical casing also accurately fitting said port, said cylinder being adapted to be closed and opened from the interior thereof, a second cylindrical plug adapted to accurately fit said port, and means for exerting pressure from the interior of the vessel to displace the first-named plug by the casing, and for thereafter displacing the casing by the second plug whereby the casing is expelled through said port while the port is maintained closed at all times.

4. In a safety device for submarine vessels, a container consisting of an elongated cylin-

- drical shell having a detachable upper section divided longitudinally with releasable means in the interior of said section for retaining the parts thereof together.
5. In a safety device for submarine vessels, a container consisting of an elongated cylindrical shell having a detachable upper section adapted to be threaded to the body of the container, said top section being divided longitudinally, with releasable means in the interior of said section for retaining the parts thereof together.
10. In a safety device for submarine vessels, a container consisting of a plurality of cylindrical sections threaded together longitudinally, and means in the interior of the container for separating an upper section to permit escape of an occupant of the container.
15. In a safety device for submarine vessels, a container consisting of an elongated cylindrical shell having a detachable upper section divided longitudinally with releasable means in the interior of said section for retaining the parts thereof together, and means operative only when said parts are held together for clamping the said upper section to the body of the container.
20. In a safety device for submarine vessels, the combination with a wall construction including a cylindrical chamber having ports opening both interiorly and exteriorly of the vessel, closures operative from the interior of the vessel to open and close the ports as required, a cylindrical container adapted to neatly fit within the chamber and insertable through the said interior port, a valved pipe system connecting the inner end of the chamber with the exterior of the vessel, and pumping means in said system for injecting water under pressure into the chamber to expel the container through the outer port and to reverse the flow from the chamber to the exterior of the vessel when the outer port is closed.
25. In a safety device for submarine vessels, the combination with a wall construction including a cylindrical chamber having ports opening both interiorly and exteriorly of the vessel, closures operative from the interior of the vessel to open and close the ports as required, a cylindrical container adapted to neatly fit within the chamber and insertable through the said interior port, a valved pipe system connecting the inner end of the chamber with the exterior of the vessel, pumping means in said system for injecting water under pressure into the chamber to expel the container through the outer port and to reverse the flow from the chamber to the exterior of the vessel when the outer port is closed, and a check valve for admitting air to the chamber from the interior of the vessel as the water is withdrawn.
30. In a safety device for submarine vessels, the combination with a wall construction including a cylindrical chamber having ports opening both interiorly and exteriorly of the vessel, a plug secured in said exterior port and normally closing the latter, a closure for the interior port of said chamber, a cylindrical container adapted for insertion within the chamber through said interior port, a second plug adapted for insertion in the chamber behind the container, said plug being adapted to neatly fit within the chamber and within the outer port thereof whereby the said plug is adapted to replace the first-named plug as a closure for said outer port, and means for applying fluid pressure to the inner end of said chamber to force the inner plug outwardly into a position within and closing the outer port whereby the first-named plug and the said container are expelled from the vessel.
35. In a safety device for submarine vessels, the combination with a wall construction including a cylindrical chamber having ports opening both interiorly and exteriorly of the vessel, a plug secured in said exterior port and normally closing the latter, a closure for the interior port of said chamber, a cylindrical container adapted for insertion within the chamber through said interior port, a second plug adapted for insertion in the chamber behind the container, said plug being adapted to neatly fit within the chamber and within the outer port thereof whereby the said plug is adapted to replace the first-named plug as a closure for said outer port, and means for applying fluid pressure to the inner end of said chamber to force the inner plug outwardly into a position within and closing the outer port whereby the first-named plug and the said container are expelled from the vessel, said container neatly fitting within the said chamber whereby the said chamber is continuously sealed to prevent passage of fluid between the walls of the chamber and the container.
40. In a safety device for submarine vessels, the combination with a wall construction including a cylindrical chamber having ports opening both interiorly and exteriorly of the vessel, a plug secured in said exterior port and normally closing the latter, a closure for the interior port of said chamber, a plurality of complementary sections and means for securing said sections together in longitudinal relation to form a cylindrical container adapted for insertion within the chamber through said interior port, at least one of said sections being displaceable from the interior of the container, a second plug adapted for insertion in the chamber behind the container, said plug being adapted to neatly fit within the chamber and within the

outer port thereof whereby the said plug is adapted to replace the first-named plug as a closure for said outer port, means for applying fluid pressure to the inner end of said chamber to force the inner plug outwardly into a position within and closing the outer port whereby the first-named plug and the said container are expelled from the vessel, and means for preventing inward displacement of the said plug from the outer port by external pressure.

13. In a submarine safety device, the combination with a wall construction comprising a cylindrical chamber, the walls of said chamber being recessed for reception of packing elements, a smooth-faced cylindrical plug adapted for insertion within the chamber, said plug neatly fitting within the said chamber and forming with said packing elements an effective seal preventing passage or fluid through the port, a smooth-faced cylindrical container adapted to displace the said plug from the interior of the vessel and also fitting neatly within the said chamber whereby an effective fluid seal is formed between the casting and the walls of the chamber, and means for applying fluid pressure to the chamber to discharge the said container therefrom.

ANTHONY E. WEINGARTNER.
